US00D530325S

(12) **United States Design Patent** (10) **Patent No.:** **US D530,325 S**
Kerila et al. (45) **Date of Patent:** **** Oct. 17, 2006**

(54) **PERIPHERAL DEVICE**

(75) Inventors: **Larry Kerila**, San Jose, CA (US);
Michelle Yu, Hayward, CA (US);
Patrick Rada, San Jose, CA (US)

(73) Assignee: **Netgear, Inc.**, Santa Clara, CA (US)

(**) Term: **14 Years**

(21) Appl. No.: **29/233,436**

(22) Filed: **Jun. 30, 2005**

(51) **LOC (8) Cl.** **14-02**

(52) **U.S. Cl.** **D14/356**; D14/240

(58) **Field of Classification Search** D14/125,
D14/135-7, 156, 167, 239-40, 242-3, 256,
D14/299, 300-1, 313, 348-9, 351-4, 356-8,
D14/361, 363, 366-368, 385, 401, 433-434;
455/73, 90.3, 347; 361/679, 685-6

See application file for complete search history.

(57) **CLAIM**

The ornamental design for a peripheral device, as shown and described.

DESCRIPTION

This application is related to the following United States patent applications: Utility patent application Peripheral Device with Visual Indicators to Show Utilization of Radio Component, Ser. No. 11/173,888, invented by Patrick Rada and Smiley Kuntjoro and filed concurrently herewith; and Utility patent application for Peripheral Device with Visual Indicators, Ser. No. 11/173,984, invented by Patrick Rada and Smiley Kuntjoro and filed concurrently herewith; Each of the foregoing applications are incorporated herein by reference in their entirety.

FIG. 1 is a top view of a peripheral device, showing our new design;

FIG. 2 is a bottom view thereof;

FIG. 3 is a right side view thereof;

FIG. 4 is a left side view thereof;

FIG. 5 is a front view thereof;

FIG. 6 is a rear view thereof; and,

FIG. 7 is a top, front, right perspective view thereof.
